UNITED STATES PATENT OFFICE

2,199,335

TIME ELEMENT RELAY

Oscar S. Field, Rochester, N. Y., assignor to General Railway Signal Company, Rochester, N. Y.

Application October 14, 1938, Serial No. 234,930

34 Claims. (Cl. 200—97)

This invention relates in general to relays, and has more particular reference to relays of the time element type, which are capable of general use, but are particularly adapted for use in connection with railway signalling systems, and the like.

The present application is a continuation, in part, of my pending application Ser. No. 85,537, filed June 16, 1936, for "Time element relays."

10 In general, it is proposed, in accordance with the present invention, to provide a time element relay which responds to the energization of its controlling circuit to energize a timed circuit only after a predetermined period of time has elapsed, there being means for readily and accurately adjusting the predetermined time period to be measured.

More specifically, it is proposed to provide a magnetic relay structure of the tractive armature type which is operable, upon energization of one controlling circuit, to move an armature in one direction from a normal biased intermediate position, whereby to start the operation of a rotary contact operating means, or timing gear, by means of a constant speed electric motor, whereby to start measuring of a time interval. After this operation has occurred, a second winding on the magnetic structure is energized to operate the armature in a different direction. The last operation of the armature operates contacts controlling the external time delay or timed circuits, and also deenergizes the electric motor. The timing gear then returns to its normal position preparatory for a subsequent operation, but the relay armature is held in its last operated position as long as the relay controlling circuit is closed.

In one form of the invention, it is proposed to provide a checking means for preventing an unduly short time of operation from resulting in the above relay, in the event the rotary operating means or timing gear does not return to its starting position. More specifically, it is proposed to prevent the operation of the timing gear by the electric motor unless the gear has fully returned to its initial or starting position, and thus insure that whenever the timed circuit is closed, an accurately predetermined time has first elapsed after the energization of the relay controlling circuit.

It is also proposed, in another form of the invention, to insure that the timed circuit shall not be closed unless a proper time interval has elapsed after energization of the relay, by providing means whereby the timed circuit is held

open until not only the motor is deenergized, but until the timing gear has returned to substantially its initial or starting position.

Other objects, purposes and characteristic features of the present invention will appear as the description progresses, reference being made to the accompanying drawings showing the invention by way of example, and in no manner whatsoever in a limiting sense. In the drawings:

Fig. 1 is a rear elevational view, showing in a simplified and diagrammatic manner, a time element device embodying one form of the present invention.

Fig. 2 is a sectional side elevational view of Fig. 1, with circuit connections shown, to illustrate one method of operating this form of the invention.

Figs. 3, 4, 5 and 6 are diagrammatic views illustrating a second, and somewhat different form, of the present invention, respectively in four different operative positions.

Fig. 7 is a diagrammatic view of a third form of the invention.

Fig. 8 is a partly structural, and partly diagrammatic view, with parts separated for clarity, of the above referred to second form of the invention.

Fig. 9 is a sectional elevational view of an actual commercial device embodying the above referred to second form of the invention.

Fig. 19 is a sectional view, on line 19—19 of Fig. 18, and viewed in the direction of the arrows.

The time element device, in accordance with the first form of the invention, is illustrated in

the accompanying drawings by Figs. 1 and 2, and includes a tractive type electro-magnetic structure which has been shown in a much simplified and diagrammatic manner, as comprising two spaced electro-magnetic cores 5 and 6, joined at their upper ends by magnetic straps 7 and terminating in enlarged pole pieces 8 and 9. The cores 5 and 6 carry main windings 12 and 14 respectively, and an armature 10 is pivotally carried beneath these pole pieces 8 and 9 by pivot pins 11 to operate into a position completing the magnetic circuit between the lower ends of cores 5 and 6. This magnetic structure may be supported by an insulating top plate, and the other mechanical details may be arranged in accordance with the usual practice in railway signalling apparatus. For example, the portion of the magnetic structure thus far described may be constructed as disclosed in my prior Patent, No. 2,1824,129, granted September 22, 1931.

In the present magnetic structure, however, the pole pieces 8 and 9 are provided with rearward magnetic extension 8¹ and 9¹, which extensions carry downwardly extending cores 16 and 18 respectively, likewise terminating in enlarged pole pieces 16¹ and 18¹, and, respectively, carrying auxiliary windings 20 and 21. The ends of armature 10 are provided with depending lower magnetic extensions, or arms, 10¹ and 10², extending downwardly in front of the pole pieces 16¹ and 18¹ respectively. With this arrangement, it will be clear that armature 10 is operable upwardly from its illustrated position to magnetically interconnect the pole pieces 8 and 9, and is also operable downwardly to magnetically interconnect the pole pieces 16¹ and 18¹, through the extensions 10¹ and 10².

Armature 10 also carries a downwardly extending fork member, illustrated as two spaced arms 24, suitably attached at their upper ends to the lower face of armature 10. A timing gear wheel 25, is carried between the lower ends of arms 24. This timing gear 25 is illustrated as attached to an enlarged diameter portion of a hub 26, the hub 26 having smaller diameter end portions extending through the arms 24 to form bearings permitting rotation of gear 25 between the arms 24. The gear wheel 25 is biased in a counter clockwise direction, as viewed in Fig. 2, by a helical spring 30, attached at its inner end to the hub 26, and at its outer end to the arm 24, by means of a pin 31. The counter clockwise biased rotation of the timing gear 25, is limited by an insulating pin 34, suitably attached thereto near its outer edge and engaging one of the arms 24, as shown in Fig. 2, whereby to determine the normal, at rest, position, of gear 25.

Suitable contacts are also carried by armature 10, one of which has been illustrated in Fig. 2 as a finger 36, attached to armature 10 by insulating spacers 37, and carrying suitable low resistance contacts at its outer end. In addition to the usual circuit controlling function, the illustrated contact means is also employed to center or determine the normal position of the armature assembly. More specifically, the weight of the armature 10 and the timing gear assembly carried thereby, biases the contact finger 36 downwardly to engage a contact surface of a stationary horizontal spring finger 39, the spring finger 39 being carried at its rear portion by a rigid stop member 40, while the front end portion of spring 39 is bent downwardly and around the end of the stop member 40, whereby to limit the upward travel of finger 39.

The spring finger 39 is provided with a predetermined trapped upward biasing force which is sufficient to balance the downward force exerted thereon by finger 36, thus determining the normal position of the armature assembly. The armature finger 36 is also operable upwardly to engage a suitable fixed contact 41, and it is to be understood that various additional contacts may also be operated by armature 10, which additional contacts may be of the usual construction.

The timing gear 25 is movable, by a downward movement of armature 10, into mesh with a pinion gear 45, driven by a suitable constant speed motor M, through reduction gearing means G, but normally gear wheel 25 is held in its illustrated position, and out of mesh with pinion gear 45. In this embodiment of the invention, motor M is operated on alternating current energy, and may be of the self-starting synchronous type, such as used in electric clock mechanism, and the like. The gear mechanism G may also be of the type used in clocks; or any suitable gear reduction arrangement operable to drive pinion gear 45 in a counter clockwise direction at a slower speed than the speed of motor M, may be employed. The present device, however, is not limited to an alternating current motor, or a gear mechanism of this type, as any self-starting means for operating the pinion gear 45 at the desired constant speed may be used, and motor M may be of the constant speed direct current type.

A means is provided for preventing the timing gear 25 from being moved into mesh with pinion gear 45, except when 25 is in its normal illustrated position. This means comprises an arm, or detent, 50, operating about a pivot pin 51, and normally resting in a horizontal position against a stop pin 52. The free end of detent 50 extends into the path of movement of gear 25, when moved toward pinion 45, but when gear 25 is in its normal illustrated position, a notch 54, therein, receives the end of detent 50 and allows gear 25 to mesh with pinion gear 45. The operation of gear 25 in a clockwise direction by pinion 45 then lifts the end of detent 50 to a position permitting continued rotation of wheel 25, inasmuch as detent 50 will then ride upon the edge of wheel 25.

The insulating pin 34 of timing gear 25 is employed to operate contacts after rotating in a clockwise direction from its illustrated position, and these contacts have been illustrated, in Fig. 2, as a flexible finger 56 normally contacting with a rigid back finger 57, and operable by pin 34 to disengage back finger 57 and engage a front finger 58. These fingers 56, 57 and 58 are shown in front of timing gear 25 with their supporting means removed. These fingers 56, 57 and 58, however, are actually carried by projections 59 on an insulating drum or dial 60, as shown in Fig. 1, and the dial 60 is provided with a hub 60¹, extending through a stationary member 62, whereby dial 60 can be rotated substantially concentrically with gear 25.

A manually operable means for rotating dial 60 from the top of the present relay, is provided by a vertical shaft 65, operable from its upper end, by a knob 66, and provided with a gear 68 at its lower end, meshing with gear teeth formed around the side of dial 60. In this manner, dial 60 can be conveniently rotated to move contact fingers 56, 57 and 58 to various points around gear 25, whereby to adjust the travel required for insulating pin 34 to move contact 56 away from contact 57, and into engagement with contact 58. A jam nut 70 is provided on hub 60¹ of dial 60, 75

which can be adjusted to provide sufficient friction against rotation of dial 60, to prevent its movement other than by shaft 65.

The operation of the present device may be explained with reference to Fig. 2, which shows one method of connecting the internal elements. Inasmuch as Fig. 2 is a sectional view of Fig. 1, only one half of the magnetic structure, comprising only one main winding 12 and only one auxiliary winding 20 would ordinarily be shown, but in order to show the electrical connections of the various elements in connection with Fig. 2, the other main winding 14, and the other auxiliary winding 21 has been illustrated to the left of windings 12 and 20 respectively, the actual mechanical arrangement of these parts, however, being as shown in Fig. 1.

The present time element device is illustrated as operable from an alternating current source of energy, and is controlled by a switch S, which can be a manually operable switch, or contacts on a relay, or any other device by which the present time element relay is to be controlled. When switch S is closed, motor M is energized to rotate pinion gear 45 in a counter clockwise direction, by current flowing from one terminal of an alternating current source, AC, through switch S, over wires 75 and 76, through contacts 56-57, wire 77, through contacts 36 and 39, wire 78, through the motor M, and back to the other terminal of alternating current source AC over wires 79 and 80.

The main windings 12 and 14, are likewise energized when switch S is closed, but when the relay is controlled from an alternating current source, as illustrated, the windings are energized alternately with undirectional current, through rectifier units 83 and 85 respectively. In other words, current during one half of an alternating current cycle, flows from the source AC, through switch S, over wires 75 and 81, through winding 12, wire 82, rectifier unit 83, and back to the other terminal of the source AC, over wire 84. During the other half of the alternating current cycle, current flows in the opposite direction through this circuit, and consequently is blocked by rectifier 83, but passes through the oppositely arranged rectifier 85, to now flow through wire 86 and winding 14, instead of wire 82 and winding 12. The windings 12 and 14 are arranged, as shown, so that a unidirectional flux in their common magnetic circuit is produced by this alternate energization.

The contacts 36 and 39 of the present device are adjusted to position the armature, as shown in Fig. 2, wherein the air gap separating the armature extensions 10¹ and 10² from the lower pole pieces 16¹ and 18¹, is considerably shorter (or has less reluctance), than the air gap separating the main portion of the armature 10 from the upper pole pieces 8 and 9. In this manner, a considerably greater portion of the total flux produced by the energization of main windings 12 and 14, flows through this shorter air gap; that is, the greater part of flux flows, for example, downwardly through core 12, downwardly through core 16, into armature extension 10¹, through armature 10, through armature extension 10², and upwardly through cores 18 and 6. Consequently the armature extensions 10¹ and 10² are attracted toward pole pieces 16¹ and 18¹ by the energization of windings 12 and 14, which movement of the armature causes finger 36 to overcome the trapped biasing force of finger 39

and thereby engages the timing gear 25 with the pinion gear 45.

The pinion gear 45 now rotates the timing gear 25, slowly, in a clockwise direction, until the insulated pin 34 engages contact 56. When contacts 56 and 58 are closed by pin 34, auxiliary windings 20 and 21 are connected, in multiple with windings 12 and 14, respectively. In other words, the joined lower ends of windings 20 and 21 are connected to the joined lower ends of windings 12 and 14, over wire 88, through contacts 58-56, and over wires 76 and 81.

The auxiliary windings 20 and 21 now being connected in multiple with the main windings 12 and 14, respectively, are energized with corresponding directions of current, but these auxiliary windings 20 and 21 are arranged in a manner relatively opposite to their respective multiple windings 12 and 14 so that winding 20 produces a flux opposing that produced by winding 12 and winding 21 produces a flux opposing that produced by winding 14. Consequently, it will be clear that the flux previously flowing through the lower cores 16 and 18 will be greatly reduced, or may be entirely eliminated, if the magnetic structure is properly proportioned. The armature extensions 10¹ and 10² will now no longer be attracted toward the pole pieces 16¹ and 18¹, but the flux produced by energization of the main windings 12 and 14 will now flow between pole pieces 8 and 9, and through the main portion of armature 10, regardless of the increased air gap, thereby resulting in an upward attraction of the armature.

Motor M was deenergized as soon as pin 34 disengaged contact 56 from contact 57, and the upward attraction of armature 10 disengages the timing gear 25 from pinion gear 45 and allows spring 38 to return gear 25 in a counter clockwise direction to its normal position. Energization of motor M is prevented, after contacts 56-57 close, by the disengagement of contact 36 from contact 39. The upward attraction of armature 10 also engages contact 36 with contact 41, to complete the time delay, or timed, circuits; as in Fig. 2, a relay R is shown, merely for example, as a means controlled by the present time element device. This relay R is energized, upon the attraction of armature 10, over a circuit passing from one terminal of the alternating current source AC, through switch S, wires 75 and 76, contacts 56-57, wire 77, contacts 36-41, wire 91, through the windings of relay R, and back to the other terminal of the alternating current source over wires 92 and 88.

The windings 20 and 21 are, of course, deenergized, as soon as pin 34 allows contacts 56 and 58 to open, upon the attraction of the armature, but armature, 10 still remains in its upper position against pole pieces 8 and 9, due to the small air gap through which the flux produced by the energization of windings 12 and 14 flows, in passing between pole pieces 8 and 9. When switch S is opened, windings 12 and 14 are deenergized and the armature immediately returns to its normal, illustrated, position. Inasmuch as the timing gear 25 has previously assumed its normal position, the operation of the device may be repeated immediately after armature 10 thus assumes its normal position.

A time element device has thus been provided wherein the closing of its controlling circuit starts a constant speed motor, and applies energy to one winding on its magnetic structure, to operate an armature in one direction which starts

- operation of a rotary contact operating means, by the constant speed motor. The contacts operated thereby, can also be positioned so that various lengths of time may be required before this rotary operating means completes a circuit energizing a second winding on the magnetic structure, which operates the armature in a different direction, thereby deenergizing the motor and operating the contacts for the external time controlled circuits.

The armature remains in its last operated position as long as energy is applied to the controlling circuit, but energy is only consumed by one of the windings of the magnetic structure, the other winding and the motor being deenergized. The rotary contact operating means also immediately returns to its normal position preparatory for a subsequent operation, but in the event some abnormal condition prevents the return of this contact operating means to exactly the proper starting position, the motor can not again function to close the contacts operated thereby, thus preventing such an abnormal condition from causing a shorter than contemplated operating time.

It will also be clear that the normally made contacts 56 and 57, which are included in the energizing circuit for motor M, as well as the external time controlled circuit, checks the proper return of the movable contact 56 to its normal position, after operation. In other words, if some abnormal condition causes contact 56 to stick in a position engaging contact 58, the external time controlled circuit to relay R cannot be closed and the motor M cannot be energized, due to the open circuit at contacts 56 and 57, thereby preventing such an abnormal condition from allowing the external time controlled circuit to be closed immediately after closing the control switch S.

In describing this first form of the invention, attention has been directed to one specific embodiment thereof, without attempting to point out the various alternate or optional features of construction, or the different organizations or combinations that may be provided. For example, if the motor M is to be operated from a direct current source, the rectifiers 83 and 85 will, of course, be unnecessary, and the windings of the magnetic structure will be energized directly from the controlling circuit. It will also be clear that in the event the controlling means S is located at a remote point, requiring a long control circuit, the auxiliary windings 20 and 21 may be energized from a separate local source of energy. Likewise under such conditions, the motor M could be energized locally through a contact (not shown), operated by armature 10, to close the motor energizing circuit only when the armature is operated downwardly from its normal position, due to the energization of the main windings 12 and 14 only.

A second form of this invention, which differs slightly both in structure and circuit arrangement, from the form described above, is illustrated in a wholly diagrammatic manner in Figs. 3-6 inclusive. In these figures the parts are shown in various different operative positions.

Referring to Fig. 3, it can be seen that the magnetic structure is substantially identical with that described in connection with the first form. This structure involves two main cores 93 and 94, carrying main windings 95 and 96; and two auxiliary cores 97 and 98, carrying auxiliary windings 99 and 100. The upper ends of the two main cores are interconnected by back straps

100¹, while the lower ends of the main cores are connected to the upper ends of the auxiliary cores, by laterally extending magnetic members 101 (only one of which can properly be shown in the figure in question). 5

Likewise, the armature has an upper portion 102 and lower depending portions 103 (only one of which can properly be shown in this figure), for coacting with main pole shoes 104, and auxiliary pole shoes 105, by movement on its pivots 10 106, in the same manner as in the above described first form of invention.

Carried by the armature, by means of insulating blocks 107, are contact fingers, such as 108 and 109, coacting with front contacts 110 and 111 respectively, and back contacts 112 and 113 respectively.

The timing gear 114, is pivoted at 115, to arms 116, which are carried by the armature, whereby the timing gear can be moved by the armature 20 to mesh its teeth 117, with the pinion gear 118, on the driving motor M¹, which motor, in this particular case, is shown as a constant speed direct current motor, of any desired structure, but preferably of the type as disclosed in the Field 25 application, Ser. No. 198,928, filed March 30, 1938, for "Direct current motor."

The timing gear carries an insulated pin 119, which is positioned to operate movable contact fingers 120 and 121, to make and break with fixed 30 fingers 122 and 123, by means of a toggle operator. The toggle operator comprises a forked member 124, pivoted at 125, to a fixed part of the relay casing, and carrying a contact operating block 126. The other end of member 124 is 35 pivoted at 127, to a rod 128, slidable in a fixed support 129, and carrying a biasing spring 130.

While the operation of this form of time element device is very similar to that described in connection with the first form of the invention, 40 the structure and circuits involved are somewhat different, as appear from the above description and the following description, of the operation of the device.

Upon closing a control means, such as the switch S¹, energy is applied to the two auxiliary windings 99 and 100, in series, through contact finger 108 and its back point, to thereby attract the depending armature parts 103, to the pole shoes 103¹. In this form of invention, the relationship 50 of the air gaps between the armature in its normally biased position, as shown in Fig. 3, and the main pole pieces, and the auxiliary pole pieces, need not be as described in connection with the first form. These gaps are preferably about 55 equal, but regardless of this, it is clear that the energization of the auxiliary windings 99 and 100 can result in the movement of the armature in one direction only, and hence no differential effect need be depended upon. 60

The movement of the armature, as just described, closes normally open back contact 113, to thereby energize motor M¹, through a circuit obvious from the drawings, and to mesh the timing gear 114, with the motor pinion 118. The pin 65 119, after a period of time determined by the position of the toggle member 124, operates to snap the toggle to its opposite, and operated, position, whereby to open contact finger 121 and back point, and close contact finger 120 and back 70 point.

The closure of contact finger 120 on its back point, completes a circuit through one of the main windings; in the particular case in Fig. 3, the winding 96; whereby to produce a flux, as 75

indicated by the arrows, in a direction to oppose the flux produced by the auxiliary windings, and to overcome this flux and cause the armature to move to position the armature part 102 against the main pole shoes 104. This results in opening the circuit through the auxiliary windings, at contact finger 108 and back point, and close a circuit through contact finger 108 and front point which includes the two main windings 95 and 96, in series, to thereby stick the armature in its picked up position.

The movement of the armature to its upper position, deenergizes motor M¹, and moves the timing gear 114 out of engagement with the motor pinion 118, whereby to permit the spring 131 to return the timing gear to the position shown in Fig. 3. As it returns, the pin 119 operates the toggle to its normal position, i. e., the position shown in Fig. 3, whereby to open contact finger 120 and back point, and hence break the initial pick-up circuit through the single winding 96, and to close contact finger 109 on its front point 111, whereby to complete the timed circuit, which passes from (+), through wire 132, contact finger 109 and front point, wire 133, contact finger 123 and front point, contact finger 121, and wire 134, to (-).

It will be noted that in this second form of the invention, the initial operation of the armature is not dependent upon a differential air gap between the armature and the two pairs of pole shoes. It further will be noted that the pick up circuit for the armature includes but one of the main windings, whereby to include less inductance in the circuit than would be the case if the two main windings were included in series. This permits the flux to build up more rapidly and hence permits the armature to pick up and complete its stick circuit through back point 110, before the return of the timing gear can effect the opening of contact finger 120 and back point, which, of course, opens the pick-up circuit. Also, after being picked up, the armature is stuck up through the two main windings in series, whereby to save energy, since with the resistance greater, the current will be less, and the energy consumption correspondingly less.

In connection with the just described pick-up and stick circuits, it is contemplated that the two main windings will be comprised of the same number of turns, of the same sized wire, whereby the pick-up and the stick circuits will include the same number of ampere turns. If desired, however, in order to obtain a more speedy pick up, so that it can be more certainly assured that the armature has picked up and completed its stick circuit before the timing gear has had time to open the pick-up circuit, the main winding 96 can include the same number of turns as, or a greater number of turns than, the main winding 95, and be comprised of wire of a larger cross section, whereby to produce a greater number of pick-up ampere turns, than the stick-up ampere turns.

In one commercial application of this relay, the windings on the main cores are so arranged that the pick-up ampere turns, are approximately 50% in excess of the stick-up ampere turns.

Referring now to figures of drawing 4, 5 and 6, showing different operation positions of the time element during its operative cycle, it can be noted that Fig. 3 shows the relay in its deenergized position wherein the armature is biased, by means to be described below, to make up contact finger

108 with its back point and to position contact 109 midway between its front and back points, with the timing gear out of engagement with the motor driven pinion, and with the operating pin 119 biased by spring 131 to its initial position 5 against one edge of the bracket 116.

In Fig. 4 is shown the position assumed by the parts prior to the pin having moved to a position to operate the toggle, but after switch S¹ has been closed, and the motor has operated the 10 timing gear through a portion of its travel.

In Fig. 5 is shown the positions assumed just after the toggle has been operated, and contact fingers 121 and 120 have been, respectively, opened and closed, with respect to their back 15 points, and before the armature has picked up to disengage the drive pinion from the timing gear.

In Fig. 6 is shown the positions assumed by the parts after the cycle of operation has been completed, and the timed circuit has been completed, 20 but before the control switch S¹ has been opened. Upon the opening of switch S¹, the parts shown in Fig. 6 will return to the normal positions assumed upon deenergization, and as shown in Fig. 3. 25

Refer now to Fig. 7 in which is shown a third form of the invention, in a wholly diagrammatic manner. In connection with the second form of invention, shown diagrammatically in Figs. 3-6, it can be seen that the timed circuit is 30 completed after the armature has picked up and the timing gear has returned sufficiently to cause the pin 119 to move the toggle back to its original position. This of course, occurs at a point of the travel of pin 119, a considerable distance before 35 it reaches its final position, and although it requires only a fraction of a second for the pin to move from this position to return the toggle, to its final position, still, if the parts should become blocked, or spring 131 should break, and the pin should not be returned to its original position, the timed circuit would be completed, and the next operation of the time element would result in giving a time interval which is shorter than intended. In other words, in this second 40 form of the invention, there is a check against the timing gear not starting to return, but there is 45 no check requiring that it be fully returned.

In the third form of invention, as shown in Fig. 7, the return of the timing gear to its initial position, is checked, whereby, if, for any reason whatsoever, the timing gear does not return to its original position, the timed circuit is not completed. 50

While the schematic showing of Fig. 7 is quite different from the actual structure employed, as will be readily apparent, as the description progresses, it is believed that a brief consideration of Fig. 7 will aid in an understanding of the manner in which this third form of invention 55 operates to check the complete return of the timing gear.

In Fig. 7 is shown a drive motor M², which is of the direct current type, and can be of a construction such as referred to above in connection with the second form of invention. This motor drives a pinion 135, which at times engages with teeth 136, on a timing gear 137, normally positioned by a biasing spring 138, to assume an initial position against a fixed stop 139. Carried by 60 the timing gear 137 is an arm 140, which, in the initial position, as shown, bears against a detent 141, on a ratchet member 142, having ratchet teeth 143, and a projecting pin 144.

The ratchet member 142 carries an arm 145, 75

received in a slot 146, in a contact operator 147. The contact operator has connected to it, at 148 and 149, two movable contact fingers 150 and 151, coacting with fixed contacts 152 and 153, carried by contact fingers 154 and 155, the contact finger 154 having a pressure arm 156 and a stop arm 157. Contact finger 155 has an inwardly projecting end portion 158, which first contacts, upon movement of member 147, with the side of contact finger 151, and as the movement continues, slides along finger 151 to finally reach the end and snap thereover, whereby to produce a snap action contact between the finger 151, and its back contact 153.

15 The contact fingers, and contact operator 147, are all carried on a dial 159, which has a means for adjusting its initial position, as in the case with the other forms of invention described. This adjusting means includes teeth 160, on the dial, 20 coacting with a pinion 161, on a stem 162, and operable by means of a head 163. The dial 159, and the ratchet member 142, are interconnected, so as to normally move together, but upon a movement of the ratchet wheel, in a downward 25 direction as viewed in Fig. 7, and relative to dial 159, the contact operator 147, is moved against the spring tension of the contact fingers, to first open contact finger 150 and back point, and then later to close contact finger 151 and back point.

30 While the core and coil structures involved in this third form of the invention have not been shown in Fig. 7, they are the same as in the second form described, so it can be readily understood, from what has preceded, that, as in the 35 second form of invention described, upon energizing the timing element device, the armature is pulled down, to energize motor M² and mesh the teeth 136 on the timing gear with the drive pinion 135. Pinion 135 then operates to move the 40 timing gear against the tension of spring 138, to first cause arm 140 to move out from under the detent 141, and hence to engage teeth 143. A short time before the time to be measured elapses, arm 140 engages pin 144, to thereby move ratchet 45 member 142, and with it arm 145, to in turn move contact operator 147, in a downward direction, as viewed in Fig. 7. This movement of the contact operator first opens contact finger 150 and back point, and hence opens the timed circuit, in the 50 same manner as with contact finger 121, and back point, of Fig. 3.

Shortly thereafter, contact finger 151 and back point snap closed, to thereby complete a pick-up circuit, in the same manner as accomplished in 55 Fig. 3, by contact finger 122 and back point. This results, in causing the armature to pick up, in de-energizing the motor, and in moving the timing gear out of mesh with the motor pinion to permit the spring 138 to return the timing gear to its 60 initial position.

In the case of this third form (Fig. 7), the return of the timing gear 137, must be practically completed before arm 140 reaches the position where it can raise detent 141, and allow the contact fingers, under the urge of their trapped tension, to return to the positions shown in Fig. 7, and, by way of arm 145, return the ratchet member 142 to its initial position, as shown, and with respect to its interconnected dial 159.

70 Thus, it can be appreciated, that the timed circuit is not completed, until the timing gear has returned substantially to its initial position. Furthermore, contact 153 which, when closed, completes the pick-up circuit for the armature, remains closed until the timing gear has fully re-

turned to its initial position, and hence remains closed a longer time than in the case of the second form, described above. This permits the armature a longer period for pick up, in order to complete its stick circuit, and hence makes the device less marginal than in the second form. With such an increase in the time during which the pick-up circuit is closed, it is entirely possible that the pick-up circuit could include the two main windings in series, but in order to provide a very possibly redundant operation margin, it is contemplated that the circuit arrangement in connection with this third form of invention, will be the same as that described in connection with the second form of invention.

10 Referring now to Fig. 8, there is here shown in a somewhat diagrammatic, but also in a somewhat structural form, an embodiment of the second form of invention. The circuit arrangement is exactly the same as described above in connection with Fig. 3. In this Fig. 8, it can be readily seen just how the magnetic structure is arranged, and just how the various parts are mounted, and supported, and adjusted.

15 In Fig. 8 can be seen the main and auxiliary cores, with the main cores interconnected at their upper ends by the back strap 100¹, and with the lower ends of the main cores interconnected to the upper ends of the auxiliary cores, by the horizontal extending portions 101. Carried by the armature is the timing gear 114, supported by a bracket 164. As explained in connection with the diagrammatic showing of this second form of invention, the pin 119, carried by the timing gear, operates toggle 124 to control the sets of contacts 121—123 and 122—120.

20 The toggle operated contacts are adjustable in position, so as to vary the timing of the device, in much the same manner as set forth in connection with the first described form of invention. These contacts are carried by a dial 165, having teeth 166, that mesh with a pinion 167, carried by an adjusting stem 168, having a thumb screw 169, for turning the same, whereby the position of the contacts can be varied. The stem 168 bears, at its lower end, against a fixed portion 170 of the casing, and carried by this portion 170, is a pointer 171, adjustable by means of a slot and coacting screw 172, to initially adjust the pointer and care for inaccuracies during the manufacture of the device. Marked on the dial can be various numbers, coacting with the pointer, to indicate the time to be measured by the device.

25 Referring now to Fig. 9, which shows the structure of a commercial form of the second form of invention, it can be seen that the pointer 171 is adjusted, by means of the stem 168, as just described, and the stem 168 can be held in adjusted position, by means of a set screw 173, or the like. Also, the means for turning the stem 168, can be 30 in the form of a slotted end 174, and this end can be normally protected against misuse by a cap 175, carrying an opening 176, for a sealing means (not shown).

35 In Fig. 9 can be seen the position of the motor M¹, which is spring mounted on a pivoted bracket 200 by a stem 177, passing through a fixed portion 178, of the device, and receiving a head 179, and a sleeved spring 180, whereby to resiliently support the motor.

40 The device as a whole, is received within a casing 181, which can be made of glass or other thermo-plastic material, and is preferably transparent, whereby to facilitate inspection. Casing 181 is connected to a top plate 182, of insulating 45

material, by means of a threaded stem 183, carrying a tightening nut 184 on its outer end.

In Fig. 10 is clearly shown the position, in the casing, of one of the auxiliary windings, together with the adjusting means for the dial, and the position assumed by the armature 102—103, with respect to the main pole shoes 104, and auxiliary pole shoes 103.

Referring to Figs. 11 and 15, there is here shown, in considerable detail, a means for adjusting the tension of spring 131 which biases and returns the timing gear. As best seen in Fig. 15, timing gear 114 carries an annular boss 183, fastened thereto by pins 184, to thus form a cup shaped member within which is received spring 131. Covering this cup is a top plate 185, having a plurality of notches 186, in its periphery, to receive an inturned finger 187, on support arm 116, whereby to hold plate 185 in fixed position with respect to carrying arm 116. Carried on spindle 115, is a hub 188, to which is fixed the top plate 185, and punched inwardly from the top plate is a holding finger 189, to which one end of spring 131 is fastened. The other end of spring 131 is fastened, at 190, to the receiving cup.

With the construction just described, it can be seen that the return spring is fastened, at one end to the timing gear, and at the other end to a member, the carrying arm 116, which is fixed relatively to the timing gear. Further, it can be seen that by pushing or springing the top plate 185 slightly inwardly, to disengage it from detent 187, the plate can be turned to adjust the tension of spring 131, and then allowed to spring back and engage one of its notches 186 with the finger 187, to maintain the adjusted position of the spring.

In Fig. 11 can be seen the spring support for motor M¹, together with an adjusting screw 191, for varying the initial position of the motor, it being apparent, when the timing gear is moved by the armature to mesh with the pinion of the motor, that the motor can move slightly, due to its spring support, to readily and accurately interengage the cooperating teeth.

In Fig. 12, and the sectional view thereof, constituting Fig. 14, is shown in detail the toggle operating member having the pivoted toggle portion 124 operated by pin 119, which, in the actual construction employed, is not round, as shown in diagrammatic Figs. 3-6, but, as here shown, is rectangular in section.

Referring now to Fig. 13, it can be seen that the external circuits connected to the time element relay, are connected by way of a plug coupler, having a detachable socket member 192, and a plug member 193, which receives the socket member 194 and which is carried by the top plate 182 of the relay. The plug and socket elements are, respectively, 192¹ and 193¹. In this Fig. 13, can be readily seen the biasing means for initially positioning the armature in a midposition, so that contact finger 109 (Fig. 3), is substantially midway between its front and back fixed points 111 and 113. This biasing means is constituted by a spring 194, received in a socket 195, in the top plate 182, and projecting downwardly to an adjusting screw 196, carried by the armature 102; and a like spring 197, positioned between an adjusting screw 198, carried by a fixed part 199 of the frame, and the depending armature portion 103. By adjusting these two springs, it can be readily appreciated that the armature can be readily biased to the desired position.

In this Fig. 13, can also be seen the actual construction of the movable contact finger 108, coacting with its front point 110, and normally making up its back point 112 (Fig. 3).

Also in Fig. 13 is shown the fixed frame portion 178, through which passes the threaded bolt 183, and to which frame the bolt is fixed by nuts 201. In this fixed part 178, is the adjusting screw 191, whereby the spring mounted motor M¹, as above described, can be adjusted on its pivot support 102.

The third form of invention, as embodied in an actual commercial structure, is shown in Figs. 17-19 inclusive, and is essentially the same as described in connection with the schematic showing of Fig. 7.

In the same manner as in the above description, a motor of the constant speed type, drives pinion 135, which can be engaged with teeth 136, on a timing gear 137, carried by a stop arm 139, 20 and positioned, as by a spring 138, to assume an initial position against the stop arm 139. Carried by the timing gear, is an extending arm 140 which, in the initial position, as shown, bears against a detent 141, which is anchored, as at 25 203, to a fixed part of the casing, and bears against a ratchet wheel 142, having teeth 143, and in turn carrying a projecting arm 144.

The ratchet wheel 142, carries an arm 145, received in a slot 146, in a contact operator 147. 30 The contact operator has connected to it, as at 148 and 149, two movable contact fingers 150 and 151, which coact with fixed contacts 152 and 153, respectively, carried by contact fingers 154 and 155. Contact finger 154 is provided with a pressure plate 156, and a stop plate 157. Contact finger 155 has an inwardly projecting end portion 158, which first contacts, upon movement of member 147, with the side of contact finger 151, and as the movement continues, this part 40 158 slides along finger 151 to finally reach the end thereof and snap thereover, whereby to produce a snap-action contact between finger 151 and its back point 153.

The contact fingers and contact operator are 45 all carried on a dial 159, which has means for adjusting it initially, as in the case of the other forms of invention described above. This adjusting means includes teeth 160, on the dial, coacting with a pinion 161, on a stem 162, which 50 can be operated manually, as described in connection with the other forms of invention. Dial 159 and ratchet member 142 are interconnected, so as to normally move together. Upon a movement of the ratchet wheel in a downward direction, as viewed in Fig. 16, the contact operator 147 has moved against the spring tension of the contact fingers, to first open contact 150 and back point, and then later to close contact finger 151 on its back point.

Arm 144, which coacts with arm 140, and through which the timing gear drives the ratchet wheel, is fastened to the ratchet wheel by means of a break-down connection. As shown in Figs. 18 and 19, this arm 144 is pivoted to the ratchet 65 wheel as at 204, near its outer end, and at its inner end, has a depressed inwardly bulging portion 205, which is received in an opening 206 in the ratchet wheel. By means of this structure, if the drive motor should fail to stop driving 70 shortly after having operated the contacts, injury might be done to the varicous parts if it were not for this break-down connection. In the event the drive continues beyond the time intended, arm 144 will turn on its pivot with 75

the depressed portion 205 moving out of the aperture 206 and thus allow the driving arm 140 to move, free from any hindrance. As can be seen in Fig. 17, there is a mutilated portion 207 in the timing gear, whereby to stop the driving by pinion 135, if the motor should overrun to any extent.

As described in connection with the schematic showing of this form of invention (Fig. 7), the 10 operation is as therein described. Pinion 135 drives the timing gear, and by means of arm 141 striking arm 144, the ratchet wheel is turned relatively to the dial 159, whereby to operate the contacts, as described above. At the start of 15 the driving of timing gear 137, arm 140 moves out from under a cam portion 208, on detent 141, to permit the detent to engage with its associated teeth. Thus, upon the contacts being 20 engaged from the timing gear, the timing gear is returned by its spring to its initial position, but the contacts are held in their operated position due to the detent holding the ratchet wheel in its operated position. It is only upon practical 25 completion of the return movement of the timing gear, that arm 140 cams the detent out of engagement with the teeth on the ratchet wheel, whereupon the contacts which are springy, and biased to the positions shown in Fig. 17, 30 rotates ratchet wheel 142 backwardly relative to the dial, and permits the contacts to restore themselves to their initial position.

In this regard, it can be seen, from Fig. 16, 35 that the ratchet wheel is rotatably mounted, at 209, on a hub 210, carried by the dial 159. With this construction, on adjusting the position of the dial by means of stem 162, the dial, with its contacts and ratchet wheel, all move together, and hence the distance between the ratchet wheel 40 arm 144 and the drive arm 141 can be varied, and hence the timing can be varied. It can be noted that even though additional parts including 45 the ratchet wheel, etc., for checking the complete return of the timing gear, have been employed, still the means for adjusting the measured time is unchanged from the other forms described above, and lends itself to the same simple type of adjustment as in the other forms 50 described.

50 The above rather specific descriptions of several forms of the present invention, have been given solely by way of example, and are not intended, in any way whatsoever, to be limiting. It is desired to be understood that all such modifications and variations in construction and arrangement of parts, as may prove desirable, are intended to be covered by the present application, except insofar as they are excluded by the scope of the appended claims.

60 Having described my invention, I now claim:

1. In a time element device, an electromagnetic structure, an armature, a first winding on the electromagnetic structure effective when energized to operate the armature in a first direction, 65 an electric motor energized when the armature is operated in said first direction, a time-measuring means driven by the electric motor when the armature is operated in said first direction, contacts operated by the time measuring means, 70 and a second winding on the electromagnetic structure controlled by the contacts for operating the armature in a second direction.

2. In a time element device, an electromagnetic structure, an armature, a first winding on the 75 electromagnetic structure effective when ener-

gized to operate the armature in a first direction, an electric motor energized when the armature is operated in said first direction, a time-measuring means driven by the electric motor when the armature is operated in said first direction, contacts operated by the time-measuring means, a second winding on the electromagnetic structure controlled by the contacts for operating the armature in a second direction, and means for restoring the time-measuring means to its original position upon operation of the armature in said second direction. 10

3. In a time element device, an electromagnetic structure, an armature, a first winding on the electromagnetic structure effective when energized to operate the armature in a first direction, 15 an electric motor energized when the armature is operated in said first direction, a time-measuring means driven by the electric motor when the armature is operated in said first direction, contacts operated by the time-measuring means, a second winding on the electromagnetic structure controlled by the contacts for operating the armature in a second direction, means for restoring the time-measuring means to its original position upon operation of the armature in said second direction, and means permitting subsequent operation of the time-measuring means by the electric motor only when the time-measuring means is restored to its original position. 20

4. In a time element relay, a pivoted armature, a first magnetic structure above the armature, a second magnetic structure joined to the first magnetic structure and extending below the armature, biasing means normally positioning the armature closer to the second magnetic structure than to the first magnetic structure, a winding on the first magnetic structure effective when energized to attract the armature toward the second magnetic structure, a winding on the second magnetic structure arranged to oppose the effect of the winding on the first magnetic structure and cause attraction of the armature toward the first magnetic structure, front and 35 back contacts operated by the armature, an electric motor energized through a back armature contact, a rotary contact operating means movable by attraction of the armature toward the second magnetic structure into a position operable by the electric motor, and contacts controlling the energization of the winding on the second magnetic structure and operated by various degrees of rotation of the contact operating means. 40

5. In a time element relay, a pivoted armature, a first magnetic structure above the armature, a second magnetic structure joined to the first magnetic structure and extending below the armature, biasing means normally positioning the 50 armature closer to the second magnetic structure than to the first magnetic structure, a winding on the first magnetic structure effective when energized to attract the armature toward the second magnetic structure, a winding on the second magnetic structure arranged to oppose the effect of the winding on the first magnetic structure and cause attraction of the armature toward the first magnetic structure, front and back contacts operated by the armature, an electric 55 motor energized through a back armature contact, a rotary contact operating means movable by attraction of the armature toward the second magnetic structure into a position operable by the electric motor, contacts controlling the energization of the winding on the second magnetic structure and operated by various degrees of rotation of the contact operating means. 60

- gization of the winding on the second magnetic structure and operated by various degrees of rotation of the contact operating means, biasing means returning the contact operating means to a normal position, and a detent for preventing movement of the contact operating means into said position operable by the electric motor except when in said normal position.

6. In a time element device, an armature movable to either of two extreme positions, means biasing the armature to an intermediate position, a substantially constant speed electric motor, a movable timing means carried by the armature, electromagnetic means coacting with the armature for moving the armature to one extreme position and the timing means to be driven by the motor, contacts operated by the timing means, means for adjusting the travel of the timing means necessary to operate the contacts, and electromagnetic means controlled by said contacts, when operated, and coacting with said armature for interrupting the drive of the timing means by the motor and moving the armature to the other extreme position.

25 7. In a time element device, an armature biased to an intermediate position, a driver driven by a substantially constant speed electric motor, a movable timing means carried by the armature, electromagnetic means coacting with the armature for moving the armature away from its intermediate position and moving the timing means into drive position with said driver, contacts operated by the timing means, means for adjusting the travel of the timing means necessary to operate the contacts, electromagnetic means controlled by the contacts and coacting with the armature for moving the armature and moving the timing means out of drive position with said driver, and means permitting movement of the timing means into drive position with said driver only when the timing means is in a predetermined normal position.

40 8. A time element device for a control circuit comprising, a driver driven by a translating device, a movable timing means, means biasing the timing means to a normal position, an armature operable in one direction to move the timing means against its bias so as to be driven by said driver, contacts operated by a predetermined movement of the timing means, and other means controlled by operation of the contacts for operating the armature in a different direction to make the control circuit effective.

45 9. A time element device comprising, a drive member driven by an electric motor, a movable timing means biased to a normal position, an armature operable in one direction to operatively connect the drive member and timing means, contacts operated by a predetermined movement of the timing means, means controlled by operation of the contacts for operating the armature in a different direction, and means permitting energization of the electric motor only when the contacts are in a normal position.

50 10. A time element device comprising a driver driven by a prime mover, a timer biased to a normal position, an armature operable to one position to operatively connect the timer and the driver, contacts controlled by a predetermined operation of the timer, means controlled by the contacts for operating and holding the armature in a second position, and contact means operated by the armature in the second position for opening the circuit for the prime mover.

55 11. In a time element device, in combination, a substantially constant speed driving means, an armature, an actuating means connected to the driving means by operation of the armature in one direction, contacts controlled by the actuating means, and means controlled by the contacts for operating the armature in a different direction.

60 12. In a time element, a translating device, a time measuring means, magnetically controlled means for energizing the device and operatively connecting the measuring means to the device, contacts operable by the measuring means, circuit means controlled by the contacts when operated to cause the magnetic means to deenergize the device and disconnect the measuring means from the device, and maintain the device and measuring means in such condition after the contacts have been restored to normal, and means for restoring the measuring means and contacts to normal.

65 13. In a time element device for controlling a timing circuit, an armature biased to an intermediate position, a drive member driven by a constant speed electric motor, a timing member carried by the armature, electromagnetic means coacting with the armature for operatively connecting the timing member and drive member, contacts operated by the timing member, means for adjusting the travel of the timing member necessary to operate the contacts, electromagnetic means controlled by the contacts, when operated, and coacting with the armature for moving the armature and moving the timing member out of mesh with the pinion gear and initiating control of said timing circuit.

70 14. In a timing device, in combination, a single magnetic core formed to provide two spaced air gaps, an armature movable to either of two extreme positions to close one or the other of said gaps, means biasing the armature to a position intermediate the two extreme positions, two separate windings on the core, connected to produce opposing m. m. f.'s when energized and arranged on the core, one between the two air gaps and the other to one side of both air gaps, and timing contacts controlled by the armature.

75 15. In a timing device, in combination, a single magnetic core formed to provide two spaced air gaps, an armature movable to either of two extreme positions to close one or the other of said gaps, means biasing the armature to a position intermediate the two extreme positions, two separate windings on the core, connected to produce opposing m. m. f.'s when energized and arranged on the core, one between the two air gaps and the other to one side of both air gaps, the armature being biased so as to move a shorter distance to close the air gap remote from said other winding than it must move to close the other air gap, and timing contacts controlled by the armature.

80 16. In a timing device, in combination, a single magnetic core formed to provide two spaced air gaps, an armature movable to either of two extreme positions to close one or the other of said gaps, means biasing the armature to a position intermediate the two extreme positions, two separate windings on the core, connected to produce opposing m. m. f.'s when energized and arranged on the core, one between the two air gaps and the other to one side of both air gaps, whereby the energization of only the winding between the air gaps causes the armature to move to close the gap remote from the other winding, and the energization of both the windings, causes the armature to move to close the other gap.

- and timing contacts controlled by the armature.
17. In a timing device, in combination, a single magnetic core formed to provide two spaced air gaps, an armature movable to either of two extreme positions to close one or the other of said gaps, means biasing the armature to a position intermediate the two extreme positions to form a longer air gap between the armature and the core at one gap than at the other, two separate windings on the core, connected to produce opposing m. m. f.'s when energized and arranged on the core, one between the two air gaps and the other to one side of both air gaps, the air gap between the armature and core and remote from said other winding being shorter than that between the armature and the other air gap, whereby the energization of said other winding causes the armature to move to close the gap remote from the energized winding, and the energization of both of the windings at the same time causes the armature to move to close the other gap, and timing contacts controlled by the armature.
18. In a time element relay, in combination, a pair of main cores each carrying a coil and terminating in a pole shoe, a pair of auxiliary cores each carrying a coil and terminating in a pole shoe positioned at an angle to the main shoes, magnetic means interconnecting the two sets of cores, an armature having a main and an auxiliary part pivoted adjacent the shoes, circuit means to energize the auxiliary coils to attract the auxiliary armature part to the auxiliary shoes, circuit means for energizing a main coil to attract the main armature part to the main shoes, and other circuit means, including a contact closed when the armature is attracted by the main shoes, for energizing the main coils in series.
19. In a time element relay, in combination, a pair of main cores each carrying a coil and terminating in a pole shoe, a pair of auxiliary cores each carrying a coil and terminating in a pole shoe positioned at an angle to the main shoes, magnetic means interconnecting the two sets of cores, an armature having a main and an auxiliary part pivoted adjacent the shoes, circuit means including a normally closed contact, which is opened when the armature is attracted by the main shoes, to energize the auxiliary coils in series to attract the auxiliary armature part to the auxiliary shoes, circuit means for energizing one main coil only to produce flux bucking the flux produced by the auxiliary coils and attract the main armature part to the main shoes, and other circuit means, including a contact closed when the armature is attracted by the main shoes, for energizing the main coils in series.
20. In a time element relay, in combination, a pair of main cores each carrying a coil and terminating in a pole shoe, a pair of auxiliary cores each carrying a coil and terminating in a pole shoe positioned at an angle to the main shoes, magnetic means interconnecting the two sets of cores, an armature having a main and an auxiliary part pivoted adjacent the shoes, circuit means including a normally closed contact, which is opened when the armature is attracted by the main shoes, to energize the auxiliary coils in series to attract the auxiliary armature part to the auxiliary shoes, circuit means for energizing one main coil only to produce flux bucking the flux produced by the auxiliary coils and attract

the main armature part to the main shoes, and other circuit means, including a contact closed when the armature is attracted by the main shoes, for energizing the main coils in series, the ampere turns produced by the one main coil being substantially equal to the ampere turns produced by the main coils in series.

21. In a time element device, an electromagnetic structure, an armature, a first winding on the electromagnetic structure effective when energized to operate the armature in a first direction, a translating device energized when the armature is operated in said first direction, a time-measuring means driven by the translating device when the armature is operated in said first direction, contacts operated by the time-measuring means, a second winding on the electromagnetic structure controlled by the contacts for operating the armature in a second direction, means for restoring the time-measuring means to its original position upon operation of the armature in said second direction, and a timed circuit including a front contact closed only upon movement of the armature in said second direction and a contact closed after movement of the armature in said second direction only if the time-measuring means starts to return to its original position.

22. In a time element device, an electromagnetic structure, an armature, a first winding on the electromagnetic structure effective when energized to operate the armature in a first direction, an electric motor energized when the armature is operated in said first direction, a time-measuring means driven by the electric motor when the armature is operated in said first direction, contacts operated by the time-measuring means, a second winding on the electromagnetic structure controlled by the contacts for operating the armature in a second direction, means for restoring the time-measuring means to its original position upon operation of the armature in said second direction, and a timed circuit including a front contact closed only upon movement of the armature in said second direction and a contact closed after movement of the armature in said second direction only if the time-measuring means has returned substantially to its original position.

23. A time element device for a control circuit comprising, a pinion gear driven by an electric motor, a gear wheel, means biasing the gear wheel to a normal position, an armature operable in one direction to move the gear wheel against its bias so as to mesh the gear wheel with the pinion gear, contacts operated by a predetermined rotation of the gear wheel, and other means controlled by operation of the contacts for operating the armature in a different direction to make the control circuit effective only if the gear wheel has returned to substantially its biased normal position.

24. A time element device for a control circuit comprising, a drive member driven by a translating device, a timing member, means biasing the timing means to a normal position, an armature operable in one direction to operatively connect the device member and the timing means, contacts operated by a predetermined movement of the timing means, other means controlled by operation of the contacts for operating the armature in a different direction to make the control circuit effective, one of said contacts being in the control circuit and being opened by said predetermined movement of the timing means, and

means holding said one of the contacts open until the timing means has returned to substantially its normal biased position.

25. A time element device for a control circuit comprising, a drive member driven by a motor, a movable timer, means biasing the timer to a normal position, an armature operable in one direction to move the timer against its bias so as to operatively connect it to the drive member, contacts operated by a predetermined movement of the timer, other means controlled by operation of the contacts for operating the armature in a different direction to make the control circuit effective, one of said contacts being in the control circuit and being opened by said predetermined movement of the timer, and a pawl and ratchet wheel for holding said one of the contacts open until the timer has returned to substantially its normal biased position.

26. A time element device for a control circuit comprising, a drive member driven by an electric motor, a movable timer, means biasing the timer to a normal position, an armature operable in one direction to move the timer to operatively connect to the drive member, contacts operated by a predetermined movement of the timer, other means controlled by operation of the contacts for operating the armature in a different direction to make the control circuit effective, and adjusting means for the timer biasing means.

27. A time element device for a control circuit comprising, a pinion gear driven by an electric motor, a gear wheel, means biasing the gear wheel to a normal position, an armature operable in one direction to move the gear wheel against its bias so as to mesh the gear wheel with the pinion gear, contacts operated by a predetermined rotation of the gear wheel, other means controlled by operation of the contacts for operating the armature in a different direction to make the control circuit effective, adjusting means for the gear wheel biasing means, and including, a spindle mounting the gear wheel, a hanger carrying the spindle, a plate rotatable on the spindle and engageable in various rotation positions with the hanger, and a coil spring fastened at one end to the plate and at the other end to the spindle.

28. A time element device comprising, a driver driven by an electric motor, a timer biased to a normal position, an armature operable in one direction to operably connect the timer and the driver, contacts operated by a predetermined movement of the timer, means controlled by operation of the contacts for operating the armature in a different direction and for deenergizing the motor, and a portion in the timer positioned to prevent faulty continued drive of the timer beyond its contact operating position.

29. A time element device for a control circuit comprising, a pinion gear driven by an electric motor, a gear wheel, means biasing the gear wheel to a normal position, an armature operable in one direction to move the gear wheel against its bias so as to mesh the gear wheel with the pinion gear, a contact operator, a break down drive connection between the gear wheel and the contact operator to cause the contacts to be operated by a predetermined rotation of the gear wheel, other means controlled by operation of the contacts for operating the armature in a different direction to close the control circuit at one point and deenergize the motor, and a mutilated portion in the gear wheel to prevent faulty operation of the motor from continuously driving the gear wheel.

30. In a timing device, in combination, a single magnetic core formed to provide two spaced air gaps, an armature movable to either of two extreme positions to close one or the other of said gaps, means biasing the armature to a position intermediate the two extreme positions, and two separate windings on the core, connected to produce opposing m. m. f.'s when energized and arranged on the core, one between the two air gaps and the other to one side of both air gaps, circuit means for energizing only the winding between the air gaps to cause the armature to move to close the gap remote from the other winding, circuit means controlled by said movement of the armature to also energize the other winding to cause the armature to move and close the other gap, and circuit means controlled by the last said movement of the armature to deenergize the winding between the gaps, and continue energization of the other winding.

31. In a timing device, in combination, a single magnetic core formed to provide two spaced air gaps, an armature movable to either of two extreme positions to close one or the other of said gaps, means biasing the armature to a position intermediate the two extreme positions, and two separate windings on the core, connected to produce opposing m. m. f.'s when energized and arranged on the core, one between the two air gaps and the other to one side of both air gaps, circuit means for energizing only the winding between the air gaps to cause the armature to move to close the gap remote from the other winding, circuit means controlled by said movement of the armature to also energize part only of the other winding to cause the armature to move and close the other gap, and circuit means controlled by the last said movement of the armature to deenergize the winding between the gaps, and cause the energization of all of the other winding.

32. A time element device for a control circuit, comprising, a substantially constant speed electric motor, a timing wheel, a driving connection between the motor and the wheel, means making the driving connection normally inoperative, an armature operable in one direction to make the driving connection operative, contacts operated by a predetermined rotation of the wheel, and other means controlled by operation of the contacts for operating the armature in a different direction to make the control circuit effective only if the wheel has retraced substantially its entire predetermined rotation.

33. A time element device for a control circuit, comprising, a substantially constant speed electric motor, a timing wheel, a driving connection between the motor and the wheel, means making the driving connection normally inoperative, an armature operable in one direction to make the driving connection operative, contacts operated by a predetermined rotation of the wheel, the contacts including a fixed contact finger of resilient material, a fixed contact member on the finger, a movable contact finger, a movable contact member on the movable finger and positioned opposite the fixed contact member, the outer end of the fixed contact finger, beyond its contact member, being bent inwardly toward the movable finger and slidably bearing against the movable finger adjacent its end, and other means controlled by operation of the contacts for operating the armature in a different direction to make the control circuit effective.

only if the wheel has retraced substantially its entire predetermined rotation.

34. A time element device for a control circuit, comprising, a substantially constant speed electric motor, a timing wheel, a driving connection between the motor and the wheel, means making the driving connection normally inoperative, an armature operable in one direction to make the driving connection operative, contacts operated by a predetermined rotation of the wheel, the contacts including a fixed contact finger of resilient material, a fixed contact member on the finger, a movable contact finger, a movable contact member on the movable finger and positioned opposite the fixed contact member, the outer end of the fixed contact finger, beyond its

contact member being bent inwardly toward the movable finger and slidingly bearing against the movable finger adjacent its end, the bent portion, when bearing against the movable finger, holding the contact members spaced from each other, the bent portion, upon pressure thereagainst being increased by movement of the movable finger, sliding beyond the end of the movable finger and snapping over the end thereof, and other means controlled by operation of the contacts for operating the armature in a different direction to make the control circuit effective only if the wheel has retraced substantially its entire predetermined rotation. 10
